UNITED STATES PATENT OFFICE

GEORGE H. KROGEL, OF TROY, NEW YORK

COMBINED NAME AND BELL-BUTTON PLATE

Application filed September 18, 1922, Serial No. 589,034. Renewed March 26, 1926.

This invention relates to a name plate for dwellings and the like, the general object of the invention being to provide a plate carrying the name of the occupants of the building or dwelling with means for illuminating the same.

Another object of the invention is to associate a button with the plate for ringing the door bell.

10 This invention also consists in certain other features of construction and in the combination and arrangement of the several parts, to be hereinafter fully described, illustrated in the accompanying drawings and specifically 15 pointed out in the appended claims.

In describing my invention in detail, reference will be had to the accompanying drawings wherein like characters denote like or corresponding parts throughout the several 20 views, and in which:-

Figure 1 is a fragmentary view of a door casing showing the invention in use.

Figure 2 is a section on line 2—2 of Figure 1.

25 Figure 3 is a section on line 3—3 of Figure 1.

Figure 4 is a diagrammatic view of the circuit.

Figures 5 and 6 are detail views.

30 In these views 1 indicates a part of the door casing to which the device is applied. The device consists of a cover 2 which is adapted to be fastened to the casing by the screws 3. The cover is provided with an

35 opening 4 which is closed by a transparent plate 5 under which is placed a sheet 6 of semi-transparent material which contains the name of the occupant. A bell button 7 is placed at one end of the cover and a light but-

40 ton 8 is placed at the other end, the bell button being preferably composed of black material and the other button of white material. These buttons are held in raised position by the springs 9, the spring for the button 8

45 having its end extending through a slot 10 in the end of the cover, one wall of this slot being provided with a notch 11 for receiving the spring so as to hold the same depressed and in engagement with the contact 12 which

50 is connected by the conductor 13 with the

lamp 14. The lamp socket 15 is connected by the conductor 16 with the source of supply 17, which is connected by a conductor 18 with one of the rivets 19 which connect the springs with the fibre base 20. The 55 springs are connected together by the wires 21. The terminal 22 for the bell button is connected by the conductor 23 with the bell 24, said bell being connected with the battery 17. The top of the cover contains the words 60 "Bell" and "Light" to indicate the bell button and the light button.

From the foregoing it will be seen that a person desiring to find whether or not he is at the correct residence will press upon the 65 light button to ignite the lamp and thus illuminate the name. If he is at the proper house he would then press upon the bell button to ring the door bell. If desired the occupants can keep the name illuminated by 70 placing the spring 9 in the notch 11 so as to hold the lamp circuit closed. The device presents a neat and attractive appearance and is very compact. The bell and lamp circuits are independent of each other so that one can 75 be used without the other.

It is thought from the foregoing description that the advantages and novel features of my invention will be readily apparent.

I desire it to be understood that I may make 80 changes in the construction and in the combination and arrangement of the several parts, provided that such changes fall within the scope of the appended claims.

What I claim is:-

1. A switch for sign plates having a source of illumination designed for momentary or permanent energization, including an insulating strip adapted to be secured to a fixture and having a contact, a casing secured to the fixture about and enclosing the insulating strip, said casing including outstanding walls beyond the strip and a top wall parallel to the strip and formed with an opening of less dimension than said wall, a spring plate secured to the insulating strip and overlying the contact, the end of the plate projecting through an opening in one of the outstanding walls of the casing, a push-button freely slideable in the top wall beyond the opening there- 95 100

in and overlying the spring plate to move the spring plate into engagement with the contact, and means integral with the casing to lock the spring plate in engagement with the contact.

- 5   2. A switch for sign plates having a source of illumination designed for momentary or permanent energization, including an insulating strip adapted to be secured to a fixture and having a contact, a casing secured to the fixture about and enclosing the insulating strip, said casing including outstanding walls beyond the strip and a top wall parallel to the strip and formed with an opening of less dimension than said wall, a spring plate secured to the insulating strip and overlying the contact, the end of the plate projecting through an opening in one of the outstanding walls of the casing, a push-button freely 10   15   20   25   30   35   40   45   50
slidable in the top wall beyond the opening therein and overlying the spring plate to move the spring plate into engagement with the contact, that end of the spring plate projecting beyond the casing providing a means whereby the plate may be operated with relation to the contact independently of the button.

3. A switch for sign plates having a source of illumination designed for momentary or permanent energization, including an insulating strip adapted to be secured to a fixture and having a contact, a casing secured to the fixture about and enclosing the insulating strip, said casing including outstanding walls beyond the strip and a top wall parallel to the strip and formed with an opening of less dimension than said wall, a spring plate secured to the insulating strip and overlying the contact, the end of the plate projecting through an opening in one of the outstanding walls of the casing, and a push-button freely slidable in the top wall beyond the opening therein and overlying the spring plate to move the spring plate into engagement with the contact, one edge of the opening in the outstanding wall of the casing being formed with a lateral recess to receive one edge of the spring plate when the latter is in engagement with the contact, whereby to lock the spring plate in circuit closing position.

In testimony whereof I affix my signature.
GEORGE H. KROGEL.
